UNITED STATES PATENT OFFICE.

ROBERT SHELDON MOORE, OF NEW YORK, N. Y.

PORTABLE SHELF FOR HEARSES.

1,178,258.

Specification of Letters Patent.

Patented Apr. 4, 1916.

Application filed December 8, 1915. Serial No. 65,714.

To all whom it may concern:

Be it known that I, ROBERT S. MOORE, a citizen of the United States, and a resident of the city of New York, borough of Manhattan, in the county and State of New York, have invented a new and Improved Portable Shelf for Hearses, of which the following is a full, clear, and exact description.

10 This invention relates to portable shelves and has particular reference to such devices adapted to be used on or in connection with hearses.

In my experience as an undertaker, I 15 find that there is much criticism and complaint respecting the handling of the flowers in connection with the casket. Before introducing the casket into or removing it from the hearse the flowers must be handled and 20 commonly are laid upon the ground in more or less disorder.

The primary object of this invention, therefore, is to provide a collapsible and portable shelf adapted to be carried under 25 the seat of the vehicle, or in any other convenient place and capable of being quickly attached to a side of the hearse in position to receive the flowers temporarily while the casket is being handled. After the casket is 30 placed and the flowers disposed of in the usual manner, the shelf is removed from the supporting position and put away for subsequent use.

With the foregoing and other objects in 35 view the invention consists in the arrangement and combination of parts hereinafter described and claimed, and while the invention is not restricted to the exact details of construction disclosed herein, still for the 40 purpose of illustrating a practical embodiment thereof reference is had to the accompanying drawings, in which like reference characters designate the same parts in the several views, and in which—

45 Figure 1 is a side elevation of a conventional form of hearse showing my improvement applied thereto; Fig. 2 is an inner edge view of the improved shelf; Fig. 3 is a bottom plan view of the same just after it has 50 been opened, the supporting arms being shown in nested position in full lines and in supporting positions in different characters of dotted lines; Fig. 4 is a vertical transverse section on the line 4—4 of Fig. 1; 55 Fig. 5 is an outside edge view of the device collapsed or folded; and Fig. 6 is a trans-

verse sectional detail on the line 6—6 of Fig. 3.

Referring now more particularly to the drawings, I show at 10 a body of a hearse 60 having vertical side columns 11 and 12. In various makes or styles of hearses the number of columns on each side varies and also their distance apart is by no means uniform. According to the type of hearse, I apply to 65 certain of the columns a pair of brackets 13 indicated in this instance as being connected to the columns 11. Each bracket comprises an upwardly projecting finger 13' and may be of an ornamental nature, not disfiguring 70 the vehicle in any manner.

The shelf in its preferred form comprises two parts 14 and 15 hinged together at their adjacent ends at 16, and provided at their other ends with suitable hasp devices 17 and 75 17' to hold them closed. Each part of the shelf comprises a rectangular frame and a panel 18, the panel constituting the main supporting surface of the shelf. For the purposes for which this device is intended 80 the shelf structure may be made of comparatively light material.

Each of the parts 14 and 15 carries a supporting arm 19 of a length slightly less than the length of the part and loosely pivoted at 85 20 adjacent the outer end of the shelf. These arms may be made of tubular metal and hence being possessed of the requisite strength for their purpose. The end of each arm opposite the pivot 20 constitutes a 90 sleeve 21 having its axis perpendicular to the axis of the arm and adapted to receive one of the fingers 13' of a bracket 13 when the arms are swung outwardly around their connections 20 as shown in Fig. 4. The 95 inner edge of the rectangular frame portions of the shelf is notched out as indicated at 22 to accommodate the arms giving them a considerable amount of freedom of adjustment to accommodate the shelf to various 100 lengths or distances between supporting columns of the hearse. It is to be understood, however, that the scope of the claims of this patent is not to be unnecessarily limited as to the particular length of said 105 notches 22.

Fig. 3 indicates the arms in various positions of adjustment with their sleeves 21 variously spaced. The arms 19, however, support the shelf at any points along the 110 notches 22. When the device is folded the arms may be fastened in place as shown in

Fig. 3 by straps 23 or equivalent temporary fasteners, and when so folded the device occupies a comparatively small amount of space and may be easily manipulated or put out of the way.

I claim:

1. In a device of the nature set forth, the combination of a shelf comprising two parts and hinges connecting them end to end, each 10 part comprising a rectangular frame having an edge notch, a pair of supporting arms pivoted to the frames on the inside opposite the notches and adapted to swing outwardly from the shelf along the notches, and means 15 to support the arms.
2. The combination of a shelf, comprising

a pair of rectangular frames and surface panels secured thereto, said frames being notched along one edge, a pair of arms 20 loosely pivoted at one end to the frames opposite the notches, said arms being adapted to swing outwardly from the shelf and apply at any desired points along said notches, the outer ends of the arms being provided with sleeves having axes at right 25 angles to the arms, and means coöperating with the arms to support the same and the shelf, substantially as set forth.

ROBERT SHELDON MOORE.
